UNITED STATES PATENT OFFICE.

JACOB L. BOTTEM, OF MCINTOSH, MINNESOTA.

ANIMAL-RELEASING DEVICE.

1,247,626.

Specification of Letters Patent. Patented Nov. 27, 1917.

Application filed March 17, 1915. Serial No. 14,985.

To all whom it may concern:

Be it known that I, JACOB L. BOTTEM, a citizen of the United States, residing at McIntosh, in the county of Polk and State 5 of Minnesota, have invented certain new and useful Improvements in Animal-Releasing Devices, of which the following is a specification.

This invention relates to improvements in 10 animal releasing devices and its object is to produce simple and effective means for simultaneously releasing animals from a series of stalls in a stable in case of necessity; and in normal times serving as a 15 holder for the animals. Means are also provided for releasing the animals individually when desired.

With the foregoing and other objects in view the invention consists in combination 20 and arrangement of parts to be hereinafter fully described in following specification, pointed out in the claims and illustrated in the accompanying drawings which form a part of said specification and in which—

25 Figure 1 is a sectional view in side elevation of a portion of my device.

Fig. 2 is a cross section taken on line 2—2 of Fig. 1.

Fig. 3 is a cross section taken on line 30 3—3 of Fig. 5.

Fig. 4 is a plan view of Fig. 1.

Fig. 5 is a side elevation of Fig. 4.

Like reference characters indicate corresponding parts throughout the several 35 views.

The reference numeral 1 designates one end wall of the stable and 2 the manger wall to which brackets 3 are secured that carry the casing 4 which extends through 40 the several stalls of the stable and within said casing the pull rod 5 is slidably arranged. One end of the pull rod extends through the wall 1 of the stable and is secured to the control lever 6 which is ful-

45 crumed at 7 upon the lug 8 carried by the said wall 1. A wedge pin 9 provided with a hand ring 10 that carries a cord 11 is normally projected into the normally aligned openings in the ends of the casing 1 and 50 rod 5 to retain said members in adjusted

position with relation to each other. The casing 4, in each stall, is formed with an elongated slot 12 and a metal strap 13 secured to the under side of said casing, below its slotted portion, extends about said casing 55 and is spaced away from the slotted portion thereof to serve as a protector for the angular pin 14 which is fast to the pull rod 5 and projects up through the slotted portion 60 of the casing and then parallel to said casing and normally into an eye 15 formed in the upturned end 16 of the angle piece 17 which is secured to said casing adjacent one end of each slot 12 therein. The hitching ring 18 at the end of the halter strap 19 is normally retained upon said pin 14 between the strap 13 and the end 65 16 of the angle piece 17. To release the rings 18 in the several stalls simultaneously the stop pin 9 is manually withdrawn from the rod and casing and the lever 6 moved away from the wall 1 into the position shown dotted in Fig. 1 thus moving the pull rod independently of the casing and so drawing the pins 14 out of engagement with 70 the eyes 15 and freeing the said hitching rings as also shown dotted in Fig. 1. The animals may be individually released by detaching the halter strap from the halter. 75

What is claimed is:

1. In an animal releasing device, a longitudinally slotted casing, a pull rod slidable within said casing, an operating lever for said pull rod, a wedge pin normally connecting said casing and pull rod, an angle piece formed with an upturned end having an eye disposed adjacent said elongated casing slot, an angular pin made fast to said pull rod and projected through the elongated slot in said casing and normally 85 into the said eye adjacent said slot and a protector for said pin carried by said casing.

2. In an animal releasing device, a longitudinally slotted casing, a pull rod slidable 95 within said casing, an operating lever for said pull rod, a wedge pin normally connecting said casing and pull rod, an angle piece having its upturned end formed with an eye disposed adjacent said elongated cas- 100

ing slot, an angular pin made fast to said pull rod and projected through the elongated slot in said casing and normally into the said eye adjacent said slot, and a strap secured to said casing and encircling the same and spaced above the apertured portion thereof to provide clearance and afford protection for the said angular pin.

In testimony that I claim the foregoing as my own I have hereto affixed my signature in the presence of two subscribing witnesses.

J. L. BOTTEM.
